(57) **CLAIM**

The ornamental design for a carton, as shown and described.

DESCRIPTION

The patent file contains at least one drawing executed in color. Copies of this patent with color drawings will be provided by the Office upon request and payment of the necessary fee.

FIG. 1 is a front elevation view of a carton showing our new design according to a first embodiment in which the carton is not assembled;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a front perspective view of a carton showing the carton of FIGS. 1-6 in an assembled state;

FIG. 8 is a front elevation view thereof;

FIG. 9 is a rear elevation view thereof;

FIG. 10 is a right side elevation view thereof;

FIG. 11 is a left side elevation view thereof;

FIG. 12 is a top plan elevation thereof;

(Continued)

FIG. 13 is a bottom plan elevation thereof;
FIG. 14 is a front elevation view of a carton showing our new design according to a second embodiment in which the carton is not assembled;
FIG. 15 is a rear elevation view thereof;
FIG. 16 is a right side elevation view thereof;
FIG. 17 is a left side elevation view thereof;
FIG. 18 is a top plan view thereof;
FIG. 19 is a bottom plan view thereof;
FIG. 20 is a front perspective view of a carton showing the carton of FIGS. 14-19 in an assembled state;
FIG. 21 is a front elevation view thereof;
FIG. 22 is a rear elevation view thereof;
FIG. 23 is a right side elevation view thereof;
FIG. 24 is a left side elevation view thereof;
FIG. 25 is a top plan elevation thereof;
FIG. 26 is a bottom plan elevation thereof;
FIG. 27 is a front elevation view of a carton showing our new design according to a third embodiment in which the carton is not assembled;
FIG. 28 is a rear elevation view thereof;
FIG. 29 is a right side elevation view thereof;
FIG. 30 is a left side elevation view thereof;
FIG. 31 is a top plan view thereof;
FIG. 32 is a bottom plan view thereof;
FIG. 33 is a front perspective view of a carton showing the carton of FIGS. 27-32 in an assembled state;
FIG. 34 is a front elevation view thereof;
FIG. 35 is a rear elevation view thereof;
FIG. 36 is a right side elevation view thereof;
FIG. 37 is a left side elevation view thereof;
FIG. 38 is a top plan elevation thereof; and,
FIG. 39 is a bottom plan elevation thereof.
The dashed broken lines in the figures illustrate portions of the carton that form no part of the claimed design.
